CONVERTIBLE LADDER STEP ATTACHMENT AND CARRIER

Martin J. Parker, Milwaukee, Wis., assignor to Tate-Step Corporation, Milwaukee, Wis., a corporation of Wisconsin

Filed Apr. 27, 1960, Ser. No. 60,335

Term of patent 14 years

(Cl. D15—8)

Fig. 1 is a front perspective view of a convertible ladder step attachment and carrier, showing my design;

Fig. 2 is a rear perspective view; and

Fig. 3 is a perspective view of the attachment showing same inverted for use as a carrier.

The broken line indicating the portions of a ladder in Fig. 1 are for illustrative purposes only. The present application is a continuation-in-part of my application D. 51,809, filed July 16, 1958.

I claim:

The ornamental design for a convertible ladder step attachment and carrier, as shown and described.
